UNITED STATES PATENT OFFICE.

ARTHUR L. HALLIDAY, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,457, dated September 13, 1881.

Application filed July 29, 1881. Term of patent 3½ years.

To all whom it may concern:

Be it known that I, ARTHUR L. HALLIDAY, of Youkers, in the county of Westchester and State of New York, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

On the background of this carpet are five distinct floral ornaments, that are marked respectively I, J, H, a, and b. By examining the upper part of the photograph it will appear that four figures I are set in the angles of a diamond, and that between the upper figure 15 I and the one next below it at the left is the figure J, and between the upper figure I and that next below it at the right are the figures a b, the figure H being in the center of the diamond. All the said figures are connected 20 with each other by projecting sprays, to make one harmonious design, and yet each figure in itself is of peculiar and different outline.

The figure I represents a bouquet of roses, with fern-like leaves projecting from opposite 25 sides, and also with a cactus-like fleshy branch of leaves projecting upwardly toward the left.

At the upper part, on the right of the figure I, is an angular geometrical figure, as shown.

The figure J is a bouquet of many flowers, 30 having extending from it in all directions cactus-like fleshy leaves.

The figure H is a bouquet of flowers set below an angular reversed letter S, with rose-leaves extending from the bouquet, and above 35 this angular ornament is a rose in blossom, with leaves extending sidewise and upward.

The figure a is a bouquet of roses, with leaves and sprays projecting upwardly.

The figure b is also a bouquet of roses, with short leaves projecting downward and upward, 45 and this figure appears to be set also on an angular design. Apparently isolated leaves are interspersed between the figure b and the figure H, also between the figure I and figure H, and said isolated leaves are, in fact, used to 50 fill up the space on the background that would otherwise remain blank. Each of these leaves has moss-like projections, that join it to the remaining figures.

The arrangement of bouquets, joined by 55 graceful sprays into one harmonious design, and set, many of them, upon configurations of geometrical outline, gives to this carpet a peculiar and novel appearance.

I claim—

1. The design for carpets, consisting of the figure I, substantially as shown.
2. The design for carpets, consisting of the figure J, substantially as shown.
3. The design for carpets, consisting of the figure H, substantially as shown.
4. The design for carpets, consisting of the figure a, substantially as shown.
5. The design for carpets, consisting of the figure b, substantially as shown.
6. The design for carpets, consisting of the figures I J H a b, substantially as shown.
7. The design for carpets, consisting of the figures I J H a b and the leaves with moss-like projections interspersed between said figures.

ARTHUR L. HALLIDAY.
